UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

FILLING-FEELER MECHANISM FOR BOX LOOMS.

Application filed June 17, 1922. Serial No. 569,110.

To all whom it may concern:

Be it known that I, JONAS NORTHRUP, a citizen of the United States, residing at Hopedale, in the county of Worcester and 5 State of Massachusetts, have invented certain new and useful Improvements in Filling-Feeler Mechanisms for Box Looms; and I do hereby declare the following to 10 be a full, clear, and exact description of the invention, such as will enable others skilled in the art to which it appertains to 15 make and use the same.

The present invention relates to an improvement to feeler looms and more particularly to feeler looms of the box type.

The object of the invention is to produce a weft replenishing loom of the box type of novel and improved construction in which the replenishing operation is controlled by 20 feeler mechanism in a novel and improved manner.

With this object in view, the invention consists in the box loom hereinafter described and particularly defined in the 25 claims.

In the accompanying drawing illustrating the preferred form of the invention as embodied in a box loom having two boxes, Figure 1 is an end elevation of a loom with 30 the shuttle box shown in section; Fig. 2 is a plan of a portion of the loom with the feeler and change mechanism; Fig. 3 is a side elevation of the change mechanism; Fig. 4 is a front elevation of the feelers 35 and a portion of the connections between them and the change mechanism; Fig. 5 shows the parts illustrated in Fig. 4 with one of the feelers in feeling position.

Box looms embodying the present invention are provided with a plurality of change boxes upon one side of the loom, arranged to be automatically raised and lowered in timed relation to the operation of the loom in order that the filling from the shuttles 45 may be utilized to accomplish the weaving operation. The weft replenishing mechanism is located at the side of the loom remote from the change boxes and provision is made for controlling its operation by 50 feeler mechanism arranged to feel of the thread while the shuttle boxes are vertically stationary, thus eliminating the uncertainty of action due to complications of motions.

The feeling mechanism preferably in-

cludes a plurality of feelers, one for each 55 of the change boxes, arranged to be raised and lowered with the boxes so as to maintain each feeler in a correct vertical position with relation to its box at all times. Provision is made for controlling the operation 60 of the feelers, so that the effective feeling operation, that is, the detecting operation, is performed upon the inactive shuttle at a time when the active shuttle is at the replenishing side of the loom and out of 65 the active change box. In addition, it has been found that the chafing of the thread by the filling engaging tip of the rigidly mounted feeler heretofore employed in this 70 type of loom and the thread breakage incident thereto is successfully avoided by the provision of a yieldingly mounted feeler. Heretofore it has been proposed to feel of the filling in a shuttle when the box containing the shuttle was being raised or lowered, but the longitudinal movement of the 75 shuttle at this time due to the shuttle camming itself out of the depression in the picker caused serious wear on the filling exposed to the action of the feeler. In the present 80 construction the filling feeler is yieldingly mounted so that relative motion between the feeler and the filling during the raising and lowering of the boxes is prevented.

The illustrated embodiment of the invention is described as follows: The loom frame 1, the crank shaft 2, the lay 3, the cam shaft 4, the shuttle boxes 5 and 6, are or may be constructed as is usual in box 85 looms. The boxes are raised and lowered by the rods 8, on the upper end of which 90 they are carried, which slide vertically on the lay structure, being raised and lowered by the link 9, connected at its upper end to the rocking beam 11, pivoted at 12 to 95 the frame of the machine, which rocking beam is oscillated by the pitman 13 connected at its upper end to the rocking beam 11, and at its lower end to the crank 14 which is operated by the Geneva motion 100 from the cam shaft 4. The shuttles 20 and 21 are carried in the boxes 5 and 6, respectively, and associated with each shuttle is a feeler, the feeler 22 being associated with the shuttle 20, and a feeler 23 being associated with the shuttle 21. These feelers are mounted on a bracket 24, bolted on the 105 slide 25, which is reciprocated in the bearing

26 by means of a pitman 27, connected at its upper end with the slide 25, and at its lower end to the box slide 10, mounted on the lay structure. It is apparent, therefore, that as the boxes are raised and lowered to move one or the other shuttle to active position, the feelers are likewise raised and lowered at the same time.

The feeler mechanism illustrated in the drawings includes the two feelers 22, 23, each comprising a filling engaging member 30, mounted to slide upon the end of a feeler lever 31, being pressed rearwardly in a direction to engage the filling on the bobbin by a spring 29 which yields when the filling engaging member comes in contact with the filling. Each feeler lever 31 is pivotally mounted on the stud 32 supported in the bracket 24. Springs 33 surrounding the hub of the feeler lever normally tend to turn the feeler levers in a direction to cause the filling engaging members to move away from the butts of the bobbin. The springs 33 are light springs and exert only sufficient force upon the feeler levers 31 to hold the front end thereof against a vertically arranged actuating rod 36. The actuating rod 36 is rotatably supported in a bracket 38 secured to the loom frame and is urged against the forward end of the feeler levers 31 by a relatively heavy coiled spring 40 interposed between an arm 42 upon the bracket 38 and a lever 44 secured to the actuating rod 36 to rotate therewith, by a set screw 43 as shown in Fig. 2. The lever 44 is provided with an upstanding lug 46 which extends through the slotted end 48 of a connecting link 49 by which movements of the lever are transmitted to the mechanism for controlling the operation of the weft replenishing mechanism, as will be described. A washer 50 and counter pin 51 retain the slotted end upon the lug.

During the normal operation of the loom, the feelers 22 and 23 enter the change boxes at each beat-up of the lay. Provision is made, however, for preventing either feeler from performing its effective feeling operation or its detecting function except at a time when the change boxes are stationary and when the active shuttle is at the side of the loom remote from the change boxes. In this manner the effective feeling operation is performed at a time when the boxes are stationary, upon the shuttle in the change box in inactive position and which shuttle and change box, upon the next beat-up of the lay, will be moved into active position by the box change. This result is secured by permitting the detecting action to occur only when the weft hammer is in a forward position. For this purpose, a lug 62 (see Fig. 2) extended laterally from a controller slide 64 is normally positioned directly in the path

of an oscillatory lever 66 directly connected to the link 49 and through the actuating rod 36 to the feelers 22, 23, so as to prevent the feelers from being pivotally moved under the influence of the heavy coiled spring 40. Provision is made for removing the lug 62 from the path of the oscillatory lever 66 at the time in the operation of the loom when the lay is at its front center and the active shuttle is absent from the active shuttle box and at the replenishing side of the loom. At this time, therefore, when filling is present upon the bobbin in the inactive shuttle, the engagement of the filling with the filling engaging tip of the feeler will effectively prevent the feeler from being pivotally moved under the influence of the coiled spring. If, however, at this time, critical exhaustion of the filling has been reached, then the compression of the coiled spring 40 operating through the lever 44 and the actuating rod 36 will operate to cause pivotal movement of the feeler so that the filling engaging tip will feel along the bobbin toward the butt thereof, and the movement of the lever will be transmitted through the link 49 to the oscillatory lever 66 to cause it to be swung to the right, viewing Fig. 2, and in the rear of the lug 62. The weft hammer at such time will be in a forward position, and upon the next rearward beat thereof, a latch 102 is positioned in the path of the weft hammer, as will be described, so that upon the next succeeding forward beat of the weft hammer, the controller arm 64, lever 66, and associated parts are moved forwardly and operate in a manner to be described to rock the change shaft and cause replenishment of the shuttle.

Referring particularly to Figs. 2 and 3, a controller 65 comprising a rod is adjustably secured in the controller arm 64. The controller 65 is adapted, under the above mentioned conditions of operation, to be positioned in the path of a bunter 67 mounted upon the lay and to be moved forwardly thereby a short distance sufficient to cause the lug 62, projecting from the controller arm to be moved out of the path of the oscillatory lever 66, as has been described. The controller 65 and the controller arm 64 are pivoted at 72 upon a controller slide 74 connected at 75 with the change lever 76, itself mounted upon the change shaft 78. The change shaft 78 is connected in the usual manner with the weft replenishing mechanism. The under surface 80 of the controller arm forms a cam surface with which cooperates a cam lug 82 extended laterally from the weft hammer 84. During the operation of the loom, at all times except upon the beat-up upon which the active shuttle is absent from the active change box and is at the replenishing side of the loom,

the controller 65 is maintained in an inoperative position up out of the path of the bunter 67, by the cooperation of the lug 82 upon the weft hammer with the rearward portion of the cam surface 80. As the weft hammer beats forwardly, and the cam lug 82 is brought into engagement with the forward portion of the cam surface 80, the controller arm is permitted to drop to an operative position to be engaged by the bunter 67 upon the lay upon the next forward beat of the lay. When the lay arrives at a front center upon this beat, the controller and controller arm are moved forwardly to move the lug 62 out of the path of the lever 66 as has been described, to thereby enable the feeler corresponding to the inactive shuttle to perform its detecting operation. The reciprocatory movement of the controller arm with relation to the controller slide is secured by a slotted bearing 86 for the pivot 72 of the controller arm. A coiled spring 88 received within a hollow portion 90 of the controller slide operates with the pivot to yieldingly hold the controller slide in a rearward position.

Extending outwardly from the controller arm 64 is a lug 98 arranged to cooperate with a vertically extended lug 100, upon a latch 102 pivoted at 104 in ears projecting from the side of the controller slide. At all times during the operation of the loom when the bunter does not engage the controller 65, the compression in the coiled spring 88 acting through the controller arm and lugs 98, 100, operates to cause the latch 102 to remain in the position indicated in Fig. 2 out of the path of movement of the weft hammer. When the loom arrives at the point in its operation for the performance of the effective feeling operation upon either of the shuttles, the weft hammer, it will be observed, will at such time be in its forward position and will therefore operate to prevent the latch from being swung to the left, viewing Fig. 2, as the bunter engages the controller. As the lay upon this detecting beat-up reaches its forward center, the controller arm is moved, as has been described, forwardly to a position such that the lug 62 is free of the end of the lever 66. If critical exhaustion has not been reached, then the lever 66 is prevented from being swung into a position in the rear of the lug 62 by the engagement of the filling engaging tip of the feeler with the filling upon the bobbin. If, however, critical exhaustion has been reached, then the compression in the coiled spring 40 operating through the lever serves to swing the end of the lever 66 into a position in the rear of the lug 62, then as the weft hammer beats backwardly, the pivot latch 102 is swung by the tension in a light coiled spring 110 into a position such

that when the weft hammer again beats forward, the end of the latch is in the path of the weft hammer and will be engaged thereby so that upon continued forward movement of the weft hammer, the controller arm, controller slide and associate parts are moved forwardly as a unit, oscillating the change lever and performing the weft replenishing operation. At the end of the forward movement of the controller slide a lug 112 formed integrally with the lever 66 engages an upstanding arm 114 secured to the loom frame and operates to swing the lever 66 outwardly from engagement with the lug 62 upon the controller arm so as to restore the controller arm in its normal position with relation to the controller slide. As the weft hammer beats backwardly, the parts assume their normal position.

It will be observed, therefore, that the effective feeling operation occurs upon the beat-up of the lay when the active shuttle is absent from the shuttle box and while the boxes are stationary and that the replenishment indicated or called for by such feeling action does not occur until the second beat-up of the lay thereafter. To recapitulate, in the operation of the illustrated loom, upon every second beat-up of the lay, first one shuttle and then the other is positioned in its change box, and the latter is in an inactive position. Upon this beat-up the effective feeling operation, or in other words, the detecting action of the feeler takes place. The second feeler entering the empty active change box encounters no bobbin and takes therefore no active part in the feeling operation at this time. If critical exhaustion of the filling in the shuttle in the inactive change box has been reached, then the detecting operation of the feeler prepares the control mechanism in the manner above described, so that upon the second beat-up of the lay after the detecting beat, the same shuttle is replenished at the replenishing side of the loom. At the beat-up of the lay intermediate or between two detecting beat-ups, both shuttles are in their change boxes at the same side of the loom, the boxes are changing, and the feeling mechanism is at this time rendered inoperative so that no detecting or effective feeling occurs.

It will be observed that the improved box loom possesses not only a new mode of operation, but that the construction of the feeling mechanism is simplified. The yielding feeler eliminates relative movement between the filling engaging tip and the filling upon the bobbin should relative movement between the shuttle and its change box occur, during a time when the feeler is in engagement with the filling, so that chafing and thread breakage which have heretofore occurred in this type of loom are successfully eliminated by the present construction.

Furthermore the performance of the feeling operation when the boxes are stationary renders the indication of filling exhaustion more positive and certain as there are less complicated motions required to transmit the filling indication.

Having thus described the invention, what is claimed is:

1. A box loom having, in combination, a lay, a plurality of change boxes at one side of the loom, weft replenishing mechanism on the other side of the loom, a plurality of feelers, one for each change box, means for actuating the change boxes and feelers to raise and lower them simultaneously, and means for controlling the operation of the feelers to permit the detecting action of the feelers to take place only at times when one of the shuttles is at the hopper side.
2. A box loom having, in combination, a lay, a plurality of change boxes at one side of the loom, weft replenishing mechanism on the other side of the loom, a plurality of feelers, one for each change box, means for actuating the change boxes and feelers to raise and lower them simultaneously, and means for controlling the feelers to permit the detecting action to take place upon the inactive shuttle when the active shuttle is absent from its change box.
3. A box loom having, in combination, a lay, a plurality of change boxes at one side of the loom, weft replenishing mechanism, a plurality of feelers, and means for permitting detecting action of the feelers only upon the bobbin in the shuttle in inactive position and when the active shuttle is absent from its box.
4. A box loom having, in combination, a lay, a plurality of change boxes at one side of the loom, weft replenishing mechanism, filling feeler mechanism, and means for controlling the operation of the latter to permit the detecting action upon succeeding shuttles to take place upon alternate beat-ups of the lay and when the active shuttle is at the replenishing side of the loom.
5. A box loom having, in combination, a lay, a plurality of change boxes, filling feeler mechanism, weft replenishing mechanism at the opposite side of the loom from the feeler mechanism, and means for controlling the operation of both to cause the detecting action to take place on one beat-up and if critical exhaustion of the filling is indicated, to cause the replenishing action to take place on the second beat-up of the lay thereafter.
6. A box loom having, in combination, a lay, a plurality of change boxes at one side of the loom, weft replenishing mechanism, filling feeler mechanism, and means for controlling the operation of the filling feeler mechanism and weft replenishing mechanism to permit the detecting action

to take place upon an inactive shuttle upon one beat-up of the lay and if critical exhaustion has been reached, to cause the corresponding replenishment to take place upon the second beat-up of the lay thereafter.

7. A box loom having, in combination, a lay, a plurality of change boxes at one side of the loom, weft replenishing mechanism, filling feeler mechanism on the same side of the loom as the change boxes, and a controlling mechanism for controlling the filling feeler mechanism to prevent the detecting action from taking place when more than one shuttle occupies the change boxes.

8. In a box loom, the combination of a filling feeler mechanism, weft replenishing mechanism, a weft hammer, and means for controlling the operation of both including a controller, means operative when the weft hammer is in a forward position for rendering the controller operative, and means engaging with the controller when operative for permitting a detecting action to be imparted to the feeler.

9. In a box loom, the combination of filling feeler mechanism, weft replenishing mechanism, a weft hammer, and means controlling the operation of both including a controller, a movable latch, connections between the latch and weft replenishing mechanism and means for normally maintaining the latch out of the path of the weft hammer when the latter is in a forward position on a detecting beat of the lay, and means acting during the following rearward beat of the weft hammer for positioning the latch in the path of the weft hammer upon the next forward beat of the latter.

10. In a box loom, the combination of filling feeler mechanism, weft replenishing mechanism, a weft hammer, and means controlling the operation of both including a controller, and means operative when the weft hammer is in a forward position for rendering the controller operative, and means for deferring the operation of the weft replenishing mechanism until the next forward beat of the weft hammer.

11. A box loom having, in combination, a lay, a plurality of change boxes at one side of the loom, weft replenishing mechanism, a plurality of feelers, means for moving the feelers in synchronism with the change boxes, and controller mechanism operatively connected with the feelers and the weft replenishing mechanism for preventing detecting action of the feelers when the boxes are changing and when more than one shuttle occupies the change boxes.

12. A box loom having, in combination, a lay, a plurality of change boxes at one side of the loom, weft replenishing mechanism, a plurality of feelers, means for moving the feelers in synchronism with the

- change boxes, controller mechanism operatively connected with the feelers and the weft replenishing mechanism to prevent detecting action of the feelers when the boxes are changing and when more than one shuttle occupies the change boxes, said mechanism including a controller, and means for rendering the controller inoperative between alternate beat-ups of the lay.
13. A box loom having, in combination, a lay, a plurality of change boxes at one side of the loom, weft replenishing mechanism, a plurality of feelers, means for moving the feelers in synchronism with the change boxes, a weft hammer and controller mechanism operatively connected with the feelers and the weft replenishing mechanism to prevent detecting action of the feelers when the boxes are changing and when more than one shuttle occupies the change boxes, said mechanism including a controller, connections between the controller and both the feeler mechanism and weft replenishing mechanism, and means actuated by the weft hammer for rendering the controller inoperative during the interval between alternate beat-ups of the lay.
14. A box loom having, in combination, a lay, a plurality of change boxes at one side of the loom, weft replenishing mechanism, filling feeler mechanism, a weft hammer, and means for controlling the filling feeler mechanism and weft replenishing mechanism to permit the detecting action of the filling feeler mechanism to take place upon alternate beat-ups of the lay when the weft hammer is in a forward position, said means including a controller, and means actuated by the weft hammer for rendering the controller inoperative upon the beat of the lay between the detecting beats.
15. A box loom having, in combination, a lay, a plurality of change boxes at one side of the loom, weft replenishing mechanism, filling feeler mechanism, a weft hammer, and means for controlling the filling feeler mechanism and weft replenishing mechanism to permit the detecting action of the filling feeler mechanism to take place upon alternate beat-ups of the lay when the weft hammer is in a forward position, said means including a controller, a controller arm, connections between the controller arm and weft hammer for raising the latter into an inoperative position during the beat of the lay intermediate the detecting beats, and connections between the controller arm and weft replenishing mechanism and filling feeler mechanism.
16. A box loom having, in combination, a lay, a plurality of change boxes at one side of the loom, weft replenishing mechanism, filling feeler mechanism, a weft hammer, and means for controlling the filling feeler mechanism and weft replenishing mecha-
- nism to permit the detecting action of the filling feeler mechanism to take place upon alternate beat-ups of the lay when the weft hammer is in a forward position, said means including a controller, a controller arm having a cam surface with which the weft hammer cooperates to raise and lower the controller into inoperative and operative position respectively.
17. A box loom having, in combination, a lay, a plurality of change boxes at one side of the loom, weft replenishing mechanism, filling feeler mechanism, a weft hammer, and means for controlling the filling feeler mechanism and weft replenishing mechanism to permit the detecting action of the filling feeler mechanism to take place upon alternate beat-ups of the lay when the weft hammer is in a forward position, said mechanism including a latch adapted to be engaged by the weft hammer, a reciprocating controller, a member adapted to be moved into cooperative relation therewith upon indication of critical exhaustion by the filling feeler mechanism to prevent reciprocation of the controller until the next subsequent forward beat of the weft hammer.
18. A box loom having, in combination, a lay, a plurality of change boxes at one side of the loom, weft replenishing mechanism, filling feeler mechanism, a weft hammer, and means for controlling the filling feeler mechanism and weft replenishing mechanism to permit the detecting action of the filling feeler mechanism to take place upon alternate beat-ups of the lay when the weft hammer is in forward position, said means including a latch, means for holding the latch out of position of the weft hammer upon the detecting beat-ups of the lay, means connected with the filling feeler mechanism for moving the pivoted latch into the path of the weft hammer upon the next rearward beat of the latter after the indication of critical exhaustion to thereby permit the weft hammer upon the next forward beat to engage the latch and move it, and connections between the latch and weft replenishing mechanism for operating the latter upon movement of the latch.
19. A box loom having, in combination, a lay, a plurality of change boxes at one side of the loom, weft replenishing mechanism, filling feeler mechanism, a weft hammer, and means for controlling the filling feeler mechanism and weft replenishing mechanism to permit the detecting action of the filling feeler mechanism to take place upon alternate beat-ups of the lay when the weft hammer is in a forward position, said means including a controller slide connected to the weft replenishing mechanism, a controller, a latch mounted on the slide and capable of being moved into and out of the path of the weft hammer, means for holding the latch

- out of the path of the weft hammer on detecting beats of the lay, means actuated by the feeler mechanism at critical exhaustion for permitting the latch to move into the path of the weft hammer so that upon the next forward beat of the weft hammer the latch and controller slide are moved to operate the weft replenishing mechanism.
20. A box loom having, in combination, a lay, a plurality of change boxes at one side of the loom, weft replenishing mechanism, filling feeler mechanism, a weft hammer, and means for controlling the filling feeler mechanism and weft replenishing mechanism to permit the detecting action of the filling feeler mechanism to take place upon alternate beat-ups of the lay when the weft hammer is in a forward position, said means including a controller slide, a controller arm movably mounted on the slide, a controller carried by the arm, connections between the controller and weft hammer for rendering the controller operative when the weft hammer is forward, a latch mounted on the slide capable of being moved into and out of the path of the weft hammer, means for holding the latch out of the path of the weft hammer on detecting beats of the lay, connections between the controller arm and filling feeler mechanism for rendering the latter inoperative until the controller arm is moved on a detecting beat of the lay and for permitting upon such movement of the controller arm, upon indication of critical exhaustion of the filling, movement of the latch into the path of the weft hammer so that upon the next forward beat of the weft hammer the weft replenishing mechanism is operated by movement of the latch and controller arm by the weft hammer.
21. In a box loom, the combination of weft replenishing mechanism, filling feeler mechanism, a weft hammer, and controller mechanism comprising a controller slide, a controller arm movably mounted on the slide, a controller carried by the arm, connections between the controller and weft hammer for rendering the controller operative on alternate beats of the lay when the weft hammer is in a forward position, a latch mounted on the slide capable of being moved into and out of the path of the weft hammer, means for holding the latch out of the path of the weft hammer on detecting beats of the lay, connections between the controller arm and filling feeler mechanism for rendering the latter inoperative until the controller arm is moved on a detecting beat of the lay and for permitting upon such movement of the controller arm, upon indication of critical exhaustion of the filling, movement of the latch into the path of the weft hammer so that upon the next forward beat of the weft hammer the weft

replenishing mechanism is operated by movement of the latch and controller arm by the weft hammer.

22. A box loom having, in combination, a lay, a plurality of change boxes at one side of the loom, and filling feeler mechanism having a plurality of mounted feelers mounted to yield laterally to eliminate wear on the filling in the event of relative movement between the shuttle and the box while the feeler is in engagement with the filling.

23. A box loom having, in combination, a lay, a plurality of change boxes at one side of the loom, weft replenishing mechanism, a plurality of feelers, and means for permitting the detection action of one of the feelers only upon the bobbin next to be picked, and during the absence of the active shuttle from its box.

24. A box loom having, in combination, a lay, a plurality of change boxes at one side of the loom, weft replenishing mechanism, a plurality of feelers, and means for causing them to feel of the bobbin in a shuttle in the change box next to be picked, and while the active shuttle is absent from its box.

25. A box loom having, in combination, a lay, two change boxes at one side of the loom, weft replenishing mechanism on the other side of the loom, a feeler, and means for causing the feeler to perform its feeling function on the inactive shuttle, and while the active shuttle is absent from the boxes.

26. A box loom having, in combination, a lay, two change boxes at one side of the loom, weft replenishing mechanism on the other side of the loom, a feeler, and means for causing the feeler to perform its feeling function on the inactive shuttle operating to cause replenishment on the second beat-up after critical exhaustion detection.

27. A box loom having, in combination, a lay, a plurality of change boxes at one side of the loom, filling feeler mechanism having a plurality of feelers, one for each box, such feelers having provision for lateral yielding movement during box changing to eliminate wear on the filling upon the occurrence of movement of the shuttle in being cammed out of the depression of the picker.

28. A box loom having, in combination, a lay, a plurality of change boxes at one side of the loom, and filling feeler mechanism having a plurality of feelers having provision for yielding laterally while in contact with the filling during box changing, in order to eliminate wear on the filling by movement of the shuttle in the box.

29. A box loom having, in combination, a lay, a plurality of change boxes on one side of the loom, and filling feeler mechanism having a plurality of feelers having provision for lateral movement of the feeler.

tip while in contact with the filling at the time when the feeling operation is not taking place, in order to eliminate wear on the filling due to movement of the shuttle in being cammed out of the depression in the picker during box changing.

30. A box loom having, in combination, a lay, a plurality of change boxes at one

side of the loom, filling feeler mechanism having a plurality of feelers, one for each box, mounted to yield laterally without indication of filling absence during box changing, and to move laterally with indication of filling absence during the feeling operation.

JONAS NORTHRUP.
